HAMMER ATTACHMENT

Truly M. Belgard, Alexandria, La.

Application February 23, 1954, Serial No. 411,785

2 Claims. (Cl. 254—26)

The present invention relates to an attachment for the head of a carpenter's claw hammer, the same being expressly designed and suitably constructed to appreciably increase leverage, this in such a manner as to facilitate greatly the pulling of nails, especially relatively long nails.

In carrying out the principles of the invention a spacing and fulcruming lock is provided, the same being effectually strapped on the central portion of a hammer head, that surface of the block which contacts the timber or other wooden or equivalent surface being cushioned to minimize the likelihood of scarring or otherwise marring said surface and minimizing the likelihood of undue skidding, whereby the hammer may be aptly and satisfactorily rocked, all in a manner to permit the claw to function in dislodging and withdrawing the desired nail.

Another object of the invention is to provide a simple, practical and economical attachment which is readily applicable and removable and which is characterized by a compressibly resilient, but effectively solid rubber block, the fulcruming surface of the block providing the desired arc which makes it extremely easy to pull nails and which obviates the possibility of the tapered ends of the claws of the hammer coming into contact with the wood surface.

Another object of the invention is to provide an attachment which merely adds negligible weight to the over-all hammer and which may remain permanently on the hammer after application, or is capable of being removed and set aside for handy use whenever necessary or desired.

Briefly summarized a preferred embodiment of the attachment is characterized by a compressibly resilient hammer-head fulcruming block, said block constituting a claw hammer attachment which functions to provide increased leverage and assists greatly in the act of pulling and extracting relatively long nails comprising a compressibly resilient hammer-head fulcruming block, said block being generally wedge-shaped in side elevation and arcuately curved to provide a concave surface to conformingly contact a surface of said hammer-head and convex surface to rest yieldingly against and fulcrum upon a work surface, and means carried by said block whereby it may be harnessed upon said head.

Further novelty is predicated on the construction set forth wherein the stated means comprises a pair of complementary U-shaped adapters whose arms and bight-portions embrace and are clamped upon cooperating portions of said head, the free ends of the arms straddling and being separably fastened to said block.

Other objects, features and advantages will become more readily apparent from the following description and the accompanying sheet of illustrative drawings.

In the drawings wherein like numerals are employed to designate like parts throughout the views:

Figure 1 is a side elevational view showing a claw hammer with a handle appearing in part and showing the attachment applied and illustrating the manner in which it

2

is used in pulling a nail out of a nail hole in a timber or an equivalent structure;

Figure 2 is a view in section and elevation taken on the horizontal line 2—2 of Figure 1 looking in the direction of the arrows;

Figure 3 is a perspective view of the attachment by itself;

Figure 4 is a section taken approximately on the plane of the line 4—4 of Figure 3 looking in the direction of the arrows; and

Figure 5 is a view on a smaller scale based on Figure 1 and showing the position of the claws of the hammer and the attachment when the claws are first engaged with the head of the nail which is to be pulled.

In the drawings in Figure 1, for example, the hammer is a conventional type and includes a handle 6 having a head 8 with the usual socket member 10, poll 12 and arcuate claws 14. The work piece here under consideration is denoted by the numeral 16 and the nail at 18. The attachment for spacing and fulcruming and assisting in increasing the leverage principle is shown satisfactorily, it is believed, in Figures 3 and 4. As before stated a compressibly resilient solid rubber block 20 is employed. This block in side elevation is generally wedge-shaped and it is arcuately curved. That is to say, there is a convex surface which includes a mounded heel portion 22 and a tapering portion 24 which is positioned in the direction of the claws. The concave side 26 is of a curvature to fit against and therefore conform to the socket and claw portions of the hammer, as best shown in Figure 1. The block is generally rectangular in cross-section and therefore provides substantially flat face parallel side surfaces. Embedded in each side surface is a wear and reinforcing plate 28. Each plate conforms in general contour or shape to the shape of the block. The area of the plate, however, is such that when the plate is embedded, by molding or otherwise, the marginal edges thereof are spaced from the surrounding marginal edge portions of the cooperating side surface. This provides satisfactory reinforcing and yet allows the projecting marginal portions of the rubber to provide the desired elastic or yieldable properties. The plates are partially held in place by cooperating cross-pins 30 which are best shown in Figure 4. These are at the respective forward and rear ends of the plates and block and assist in stabilizing the over-all plate-equipped block. The outer surfaces of the plates are flush with the surrounding marginal portions 32.

There are two U-shaped adapters 34 and 36 and these serve to harness or strap the block in its useful position on the head of the hammer in the manner shown in Figures 1, 2, and 5. Each U-shaped strap or adapter comprises a suitably angled bight-portion 38 and spaced parallel arms 40—40. The free end portions of the arms straddle the block and are superimposed against the metal plates. These free end portions are bolted in place. Each bolt preferably includes a hollow stem or socket member 42 and a screw-threaded member 44 which telescopes and screws into it in the manner shown. These are well known types of fasteners and serve aptly and satisfactorily in joining the respective arms to the block and plate at the desired longitudinally spaced points. These fasteners are sometimes referred to as telescoping type screws. The steel plates provide satisfactory anchorage for the U-shaped adapters. In addition, however, these plates are for security for the rubber block inasmuch as they are recessed into the side surfaces of the block and cannot scar or score the work surface.

The construction of the attachment is such, from a standpoint of simplicity and appropriateness, that a clear understanding of the details can be had from the disclosure herein provided. The method of applying and

removing the attachment and its mode of use need not, it is believed, be set forth more explicitly.

From the foregoing, the construction and operation of the device will be readily understood and further explanation is believed to be unnecessary. However, since numerous modifications and changes will readily occur to those skilled in the art, it is not desired to limit the invention to the exact construction shown and described, and accordingly all suitable modifications and equivalents may be resorted to, falling within the scope of the appended claims.

What is claimed as new is as follows:

1. A claw hammer attachment which functions to provide increased leverage and assists greatly in the act of pulling and extracting relatively long nails comprising a compressibly resilient hammer head fulcruming block, said block being generally wedge-shaped in side elevation and arcuately curved to provide a concave surface to conformingly contact a surface of said hammer head and a convex surface to rest yieldingly against and fulcrum upon a work surface, said block being rectangular in cross-section and the side surfaces thereof being flat and parallel to one another, rigid metal plates embedded in said side surfaces, the marginal edges of the plates being spaced inwardly from the corresponding marginal edges of the side surface portions of the block and being flush with said side surfaces, and a pair of complementary U-shaped adapters, the latter each including a pair of spaced parallel arms joined by way of a bight-portion, the free end portions of the arms straddling said block and plates and being separably bolted to said plates by way of complementary bolts passing through said block.

2. A claw hammer attachment which functions to provide increased leverage and assists greatly in the act of pulling and extracting relatively long nails comprising a compressibly resilient hammer head fulcruming block, said block being generally wedge-shaped in side elevation and arcuately curved to provide a concave surface to conformingly contact a surface of said hammer head and a convex surface to rest yieldingly against and fulcrum upon a work surface, said block being rectangular in cross-section and the side surfaces thereof being flat and parallel to one another, a rigid metal plate shaped to correspond with each side surface and embedded in the intended cooperating side surface, the marginal edges of the plates being spaced inwardly from the marginal edges of the side surfaces and having their outer surfaces flush with the corresponding surfaces of said side surfaces, a pair of complementary U-shaped adapters having bight portions and arm portions, the arm portions straddling the metal plates, and bolts passing through the block and through the respective plates, the free ends of said arms being separably and hingedly connected to the cooperating adjacent portions of the respective bolts.
